UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

ELECTRIC SWITCH.

Application filed October 22, 1917, Serial No. 197,782. Renewed May 22, 1924.

To all whom it may concern:

Be it known that I, MORRIS P. HOLMES, a citizen of the United States, residing at Claremont, in the county of Sullivan and State of New Hampshire, have invented certain new and useful Improvements in Electric Switches, of which the following is a full, clear, and exact specification.

- My invention relates to electric switches. 10 It has for its object to provide an improved electric switch especially adapted to use in connection with removable connectors or fuses. A further object of my invention is to provide an improved connector or fuse 16 and switch interlocking mechanism wherein the several connector or fuse connections can not be changed during current flow. A still further object of my invention is to provide improved means wherein the connector or fuse elements can not be removed while current passes through the machine, and wherein when one or more of the connector or fuse elements has been removed, current can not be supplied to the machine 20 until the missing connector or fuse element or elements have been returned to their proper position. More specifically, my invention has among its objects to provide improved and simplified operating mechanism especially adapted to use in connection with multi-phase alternating current machines in gas laden atmospheres such as those encountered in mines, and operatively connected between the connector or fuse 30 connections and the switch in such a manner that the above mentioned results may be obtained and all danger arising from the improper operation of the mechanism by an ignorant operator thus overcoming. These 35 and other objects of my improved construction will, however, be hereinafter more fully brought out.
- In order that my invention may be clearly and fully disclosed, I have shown for 40 purposes of illustration in the accompanying drawings one embodiment of the same applied to use in a mining machine, for facility of illustration showing the invention used in connection with a simplified 45 form of start and stop switch as distinguished from the more complicated starting switch such as is ordinarily employed upon a mining machine.
- In these drawings,— Fig. 1 is a side elevation of a mining machine equipped with my improvement. Fig. 2 is a vertical sectional view taken mainly on line 2-2 of Fig. 1 with parts omitted. Fig. 3 is a transverse sectional view taken on line 3-3 of Fig. 2 with parts broken away and with certain of the component parts shown in different relative positions. Fig. 4 is a sectional view similar to Fig. 3, showing the parts in a different position of adjustment.
- In this illustrative construction I have shown my invention as applied to a mining machine 1 of standard form and provided with any suitable cutting mechanism 2, herein shown as of the type adapted to cut a kerf in the coal face. More specifically, it will be noted that this machine is provided with a motor 3 and mounted upon a shoe 4, which is adapted to slide along the mine bottom, the power for feeding the same being supplied from the motor through suitable driving connections (not shown) to a flexible feeding member 5, herein shown in the form of a chain adapted to be connected adjacent the face and move relative to suitable guiding elements 6 and 7 carried on the machine frame. As in a usual mining machine construction, the movement of the machine is controlled through manipulation of a suitable friction controlling lever 8 mechanically controlling the feeding mechanism, a switch controlled by a handle 9 controlling the current supplied to the motor through a suitable cable 10.
- The switch, hereinafter referred to as the controller, may be of any desired type, as distinguished from the simplified form of controller for multi-phase circuits shown herein. In a preferred form the same is carried in an enclosed chamber 11 within the machine frame and comprises a plurality of rotatable elements or contact carrying arms 12 provided with a plurality of contacts 13 thereon adapted to cooperate with stationary contacts 14 formed in the controller casing. In order to facilitate illustration, only two of these elements 12 have been illustrated herein, but it will be understood that whenever the controller is used in an alternating circuit, one, two or the number of the same

provided in practice will depend on the phase of the current used. As usual, these elements 12 are preferably rotatable, the same being shown herein as rotatable with a suitable shaft 15 journaled in the frame and operatively connected to the controller handle 9 in such a manner as to move therewith, the elements 12 being insulated from the shaft 15 by suitable means, as for instance the insulation 16. As usual, it will also be observed that the controller handle 9 is operable from the exterior of the chamber 11 and that the same is also provided with an inner crank arm 17 disposed within the casing and adapted to hold the same in a plurality of positions through the engagement of a spring pressed plunger 18 thereon with a plurality of notches 19, herein two corresponding to the "on" and "off" positions of the controller and formed in a plate 20 carried within the machine frame. It will also be observed that, as in a usual construction, connector or fuse receiving members 21 and 22, connected to the line through connections 23 and 24, are herein provided to receive the inner ends of the connector or fuse elements. The hubs are electrically connected to the fuse receiving members by flexible connections which permit the necessary limited rotation of the hubs and contact arms 12. To facilitate the placing of the different members, prevent the crossing of wires, and permit the use of short flexible connections, the current is preferably passed through one connector or fuse to the front controller in the opposite direction to that in which the current flows in the remaining connectors or fuses. As is shown in Fig. 2, the current passing through the central fuse is taken from the line through a cable 24, and is passed through a holder 22, connector or fuse, a holder 21, and the first arm 12, to the motor. The current in the next connector or fuse is taken from the line by a cable 23 and is passed through another holder 21, connector or fuse, another holder 22, and the middle or second arm, to the motor. Thus, as in the usual construction, when the controller handle 9 is adjusted relative to its casing, the connections between the contacts 13 and 14 will be varied in a predetermined order, the current being supplied through the same when the plunger 18 is in one position and shut off from the same when the plunger is in its opposite position.

In the form of my improvement chosen for illustration herein, the invention is illustrated as applied to an alternating current machine, three connector elements, herein 60 in the form of fuse elements 25 being provided, which are disposed in alignment above the controller handle 9. As shown, the elements 25 are in the form of plugs insertable in suitable bores or openings 26 in the frame 55 concentric with but slightly larger than the openings in the fuse receiving elements 21 and 22. As shown, these elements 25 are provided with concentric larger outer ends receivable in the openings 26 and having knobs 27 formed thereon to enable them to be readily withdrawn from or inserted in the openings 26, as desired. Attention is here also directed to the fact that each of the openings 26 is also provided with a longitudinally extending groove or slot 28 there- 75 in adapted to receive a projection or spline 29 formed on the inner end of the enlarged portion of each element 25. It will also be noted that a rotatable ring member 30 is disposed around the periphery of each of 80 the openings 26 near the inner end thereof, and that this ring 30 is provided with a suitable groove or notch 31 adapted to register with the groove or slot 28 and to receive the projection or spline 29 on its element 25. 85 Thus, it will be noted that each member 25 may not be inserted in the casing until after it has been turned in such a manner that the projection or spline 29 thereon is brought into successive registry with the slot 28 and 90 the notch 31, and that thereafter the member 25 may be reciprocated relative to the casing and the ring 30 in such a manner as to cause its inner end to seat in correct position in the receiving elements 21 and 22. Obviously, 95 by rotating the element 25 and the ring 30 until the projection 29 is out of registry with the slot 28, the member 25 may be readily locked in position.

Cooperating with the fuse elements above 100 described, I have also provided means co-operating with the controller whereby these elements are interlocked. As shown, these means include a transversely reciprocable member 32 disposed within the frame and having a series of cut-away or dished-out portions or depressions 33 therein adapted to cooperate with different portions of the periphery of the rings 30 and to be locked in place when those members 30 are in predetermined positions. In a preferred form these rings 30 are also provided with flattened portions 34 thereon so that the rings may be rotated in such a manner as to bring these flattened portions 34 opposite the cut-away portions 33 in the reciprocable member 32. 110 This member 32 is, as shown, movable in a suitable grooved-out portion 35 in the inside of the controller casing and is also operatively connected to the controller handle 115 in such a manner as to be movable therewith and to control the movement thereof. In the form of my invention shown herein, this operative connection assumes the form of a rack and pinion connection, the member 32 being provided with rack teeth 36 while an element 37, rotatable with the controller handle, is provided with pinion teeth 38 meshing with the rack teeth. Thus, it will 120 be noted that while the controller may not

be moved when the fuse elements are in the position shown in Fig. 3 due to the fact that a portion of the members 30 extend into the cut-away portions 33 on the member 32, the controller may be moved with entire freedom when the fuse elements have been rotated into their locked positions shown in Fig. 4, wherein the flattened portions 34 are opposite the cut-away portions 33. Attention is also directed to the fact that an exact and quick adjustment of the parts may be insured by providing an arcuate transverse slot 39 in each of the bores or openings 26 in the frame and a pin 40 on each of the rings 30. But one of these is shown in the present drawings. However, it will be understood that the arrangements of the others would be the same. Thus, it will be noted that the ring 30 may always be turned in one operation into such position as to insure the release of the member 32 and the controller handle 9.

In the operation of my improvement, it will be observed that whenever it is desired to remove a connector or fuse element, this may be readily accomplished by first moving the controller to "off" position and then rotating the element and its ring 30 into a position wherein the groove 31 in the ring registers with the corresponding slot 28 in the casing, whereupon, the fuse element being unlocked, the same may be readily withdrawn. In this position, however, it will be observed that, as shown in Fig. 3, a portion of the periphery of the ring 30 then extends into the cut-away portion 33 in the reciprocable member 32 so that the controller may not be operated and must remain out of operation so long as the fuse element is removed. As the grooves 28 and 31 are thus left in registry when the fuse element is removed, the latter may obviously be returned to operative position without difficulty. After this occurs and the fuse element 25 and ring 30 have been rotated in such a manner as to bring the pin 40 against the end of its slot 39, it will be noted that not only is the member 25 locked in place, but the flattened portion 34 is brought opposite the cut-away portion 33 in the member 32 in such a manner that the latter may be reciprocated and the controller readily moved on the fuse element into its current-supplying position.

As a result of my improvement, it will be noted that it is rendered impossible for an unskilled operator to pull out any connector or fuse plug while current is flowing through the machine, and that it is likewise also impossible for an unskilled operator to apply current to the machine while a connector or fuse element is removed, thus effectively overcoming the difficulties in the way of explosions, etc. which have heretofore been experienced when a machine is operat-

ed in a gaseous mine by an unskilled operator. More specifically, it will be observed that the casing is thus maintained closed or sealed at all times while current is flowing, as it is impossible to open the same by the removal of a plug until the current is off and it is then impossible to supply current until the casing has been again closed by replacement of the plug, all arcing within the casing and resultant danger of igniting a gas laden atmosphere thus being avoided. It will also be noted that an exceedingly simple form of interlocking mechanism is provided which is no way interferes with the normal operation of the controller, and yet at the same time permits any individual plug or all the plugs to be readily locked in position and removed whenever removal is desired. These and other advantages of my improvement will, however, be clearly apparent to those skilled in the art.

While I have in this application specifically described one embodiment which my invention may assume in practice, it will be understood that the same may be applied to other uses than in connection with mining machines and embodied in various other forms with other circuit closers or switch devices than controllers or other connector elements than fuses, and that it is my intention to include all such modifications within the scope of the appended claims.

What I claim as new and desire to secure by Letters Patent is:

1. In an electric switch, a movable switch element, a connector comprising a single plug, and means for locking the former in open position actuated by the latter upon a removal movement thereof.

2. In an electric switch, a pivotally movable switch element, a circuit controlling connector movable in a direction substantially perpendicular to the plane of pivotal movement of said switch element, and means for locking the former in open position while the latter is removed.

3. In an electric switch, a pivotally movable switch element, a circuit controlling connector movable in a direction making an angle with the plane of pivotal movement of said switch element, and means for locking the former in open position actuated by the latter during removal movement thereof.

4. In an electric switch, a pivotally movable switch element, a circuit controlling connector movable in a direction substantially perpendicular to the plane of pivotal movement of said switch element, and means for locking the former in open position releasable upon an insertion movement of the latter.

5. In an electric switch, a movable switch element, a connector constituting a circuit

- forming element for but one line of a circuit controlled by said switch element and comprising a single plug, a socket for said connector plug, means for holding said connector plug against removal from said socket when said switch element is in circuit closing position, and means for locking the latter in open position actuated upon a removal movement of said connector plug.
6. In a controlling mechanism for electrical apparatus, a plurality of power leads, switch means for breaking the circuit through at least one of said leads, connectors each comprising a single separate plug inserted in each of said power leads, and means for locking said switch means in open position made effective upon removal of any one of said connectors.
7. In an electric circuit controlling mechanism, a switch arranged in a circuit and comprising a movable switch element, means for independently making or breaking one branch of the circuit, and means for locking the former element in open position lockable and releasable by the latter means.
8. In an electric switch, a movable switch element, a plurality of independently movable connector elements, and locking and unlocking means for said switch element controlled by each of said connector elements.
9. In an electric switch, a movable circuit closer element, a plurality of independently movable connector elements, and means for preventing movement of the former save in a predetermined disposition of the latter.
10. In an electric switch, a movable switch element, a plurality of independently removable connector elements, and means for rendering said switch element immovable upon removal of any one of said connector elements.
11. In an electric switch, a movable circuit closer element, a plurality of independently movable connector elements, and means for holding the former in open position releasable only when all of the latter are in operative position.
12. In a controller, a movable controller element, a removable connector element, and means operable by said connector element for unlocking the same and locking said controller element.
13. In a controller, a movable controller element, a removable connector element, and means operable by said connector element for simultaneously unlocking the same and locking said controller element.
14. In a controller, a controller element, a removable connector element, and means controllable by said connector element for locking the same and unlocking said controller element.
15. In a controller, a controller element, a removable connector element, and means
- controllable by said connector element for simultaneously locking the same and unlocking said controller element.
16. In a controller, a controller element, a plurality of removable connector elements, and means controlled by movement of but one of the same for unlocking said element and locking said controller element.
17. In a controller, a controller element, a plurality of removable connector elements, and means controlled by movement of any of said connector elements for unlocking said element and locking said controller element.
18. In a controller, a movable controller element, a plurality of removable connector elements, and interlocking connections between said elements controlled by any of said connector elements for locking the same and unlocking said controller element.
19. In a controller, a movable controller element, a removable connector element, and means actuated upon rotation of said connector element for unlocking the same and locking said controller element.
20. In a controller, a movable controller element, a removable connector element, and means actuated upon rotation of said connector element for locking the same and unlocking said controller element.
21. In an electric switch, a movable switch element, a removable single-plug connector element, and means actuated upon movement of the latter for releasing one of said elements and locking the other.
22. In an electric switch, a movable switch element, a removable single-plug connector, and means actuated upon a movement of the latter to a predetermined position for locking the same and unlocking said switch element.
23. In an electric switch, a movable switch element, a removable single-plug connector, and means whereby the same may be locked in circuit closing position, said means being operative upon movement of the connector to withdraw the latter to unlock the same and lock said switch element.
24. In a controller, a casing, a movable element operable from the exterior thereof, a connector element removable from the exterior thereof, and interlocking connections controlled by movement of said connector element from a predetermined position for controlling both of said elements.
25. In a controller, a casing, a movable element operable from the exterior thereof, a connector element protruding from said casing, and interlocking means between said elements for simultaneously locking one of said elements and unlocking the other thereof.
26. In a controller, a casing, a movable element operable from the exterior thereof, a connector element protruding from said

- casing, and interlocking connections between said elements controlled by a rotary movement of said connector element to a predetermined position in said casing.
27. In a controller, a casing, a movable element operable from the exterior thereof, a plurality of connector elements protruding from said casing, and interlocking connections between said elements controlled by movement of any of said connector elements to a predetermined position within said casing.
28. In a controller, a casing, a movable element operable from the exterior thereof, a connector element protruding from said casing, and means operable in a single operation to unlock said connector element and lock said movable element.
29. In a controller, a casing, a movable element operable from the exterior thereof, a connector element protruding from said casing, and means operable in a single operation to lock said connector element and unlock said movable element.
30. In an electric switch, a movable switch element, a single-pole removable connector plug, and means cooperating therewith for preventing removal of the latter while the former is in circuit closing position and closure of the former while the latter is removed.
31. In an electric switch, a movable switch element, a plurality of independently removable connectors, and means for preventing removal of any of the latter while the former is in circuit closing position and closure of the former while any of the latter is removed.
32. In a controller, a casing, a connector element protruding from said casing, and interlocking connections between said connector element and casing including a cooperating groove and a projection on said casing and connector element respectively, and a rotatable ring having a groove adapted to register with said first named groove and receive said projection.
33. In a controller, a casing, a removable connector element protruding therefrom, and means for locking the same in said casing including a rotatable ring, a movable controller element, and operative connections between said controller element and said ring.
34. In a controller, a casing, a removable connector element therein, locking connections therefor including a rotatable ring, a movable controller element, and means cooperating with the ring for locking said controller element in a predetermined position of said ring.
35. In a controller, a casing, a removable connector element therein, locking connections therefor including a rotatable ring, a movable controller element, and means
- cooperating with the ring for unlocking said controller element only in a predetermined position of said ring.
36. In a controller, a casing, a plurality of removable connector elements therein, interlocking connections therefor including a plurality of rotatable rings, a movable controller element, and interlocking connections between the latter and one of said rings.
37. In a controller, a casing, a connector element therein, interlocking connections therefor including a rotatable ring, a movable controller element, and locking connections therefor controlled by the position of said ring.
38. In a controller, a casing, a connector element therein, interlocking mechanism therefor including a rotatable ring, a movable controller handle, and means for locking the latter including a reciprocable member adapted to be controlled by said ring.
39. In a controller, a casing, a connector element therein, interlocking mechanism therefor including a rotatable ring, a movable controller element, and means for locking the latter including a rack and pinion mechanism adapted to be controlled by said ring.
40. In a controller, a casing, a connector element protruding from said casing, guiding means on said casing and element including a projection on said element, and a locking means carried by said casing including a groove disposed at an angle to said guiding means and adapted to register therewith and receive said projection.
41. In a controller, a casing, a connector element therein, interlocking mechanism therefor including a rotatable ring, a movable controller handle, and means for locking the latter including a member actuated by said handle and adapted to be controlled by said ring.
42. In combination, a multi-phase switch having a movable element, a plurality of removable connector elements electrically connectable therewith, and means for locking said movable element in open circuit position by a movement of any of said connector elements.
43. In combination, a multi-phase switch having a movable element, a plurality of individually removable connector elements electrically connectable therewith, and means for preventing movement of said movable element to circuit closing position unless all of said connector elements are in operative position.
44. In combination, a multi-phase switch having a movable element, a plurality of removable connector elements electrically connectable therewith, and means for preventing removal of any connector element while said movable element is in circuit closing

position and movement of said movable element to said position while any connector element is removed.

45. In combination, a casing having a plurality of apertures therein, a multi-phase switch in said casing, a plurality of removable connector elements disposed in and closing said apertures when in operative position and electrically connectable to said switch, and means for retaining all of said connector elements in operative position save in the open circuit position of said switch, said means being held immovable in all other positions of said switch.

15 46. In combination, a casing having a plurality of apertures therein, a multi-phase switch in said casing, a plurality of removable connector elements disposed in and closing said apertures when in operative position and electrically connectable to said switch, and means for maintaining said switch in open circuit position while any connector element is removed.

25 47. In combination, a casing having a plurality of apertures therein, a multi-phase switch in said casing, a plurality of removable connector elements disposed in and closing said apertures when in operative position, electrical connections therefor in said casing and connected to said switch, and means for preventing removal of any connector element while said switch is closed and retaining the latter in open position until return of all of said connector elements.

35 48. In a controller, a casing, a movable element operable from the exterior thereof, a connector element removable from the exterior thereof, and interlocking connections operative on movement of said connector element to a predetermined position to lock said movable element against movement and said connector element against direct withdrawal.

45 49. In combination, a rotatable controller element, a connector element, and means including a member rotatable manually while said controller element remains stationary operative in one position of said member to prevent rotation of said controller element and to permit withdrawal of said connector element.

55 50. In combination, a rotatable controller element, a connector element, and means including a rotatable member having different stationary positions to which it may be moved operative in one position of said member to prevent rotation of said controller element and to prevent direct withdrawal of said connector element.

60 51. In combination with a rotatable controller element, a connector element, and interlocking means cooperating with said elements including a rotatable member having different positions in which it will remain and in which said connector element

is respectively locked against removal and removable, said controller element being respectively unlocked and locked in such positions of said rotatable member.

52. In combination, a rotatable controller element, a connector element, and means for effecting locking of said connector element against removal including a manually rotatable member and means operative on rotation of said controller element to a predetermined position to prevent rotation of said manually rotatable member to permit withdrawal of said connector element.

53. In an electric switch, a pivotally movable switch element and means for actuating the same, a circuit controlling connector movable in a direction substantially perpendicular to the plane of pivotal movement of the switch element, and means including a member rotatable relative to said switch element for locking the former in open position moved to releasing position when said connector is disposed in a predetermined position.

54. In an electrical switch, a movable switch element, a connector constituting a circuit forming element forming but one line of a circuit controlled by said switch element and comprising a single plug, a socket for said connector plug, means for holding the connector plug against withdrawal from the socket when said switch element is in circuit closing position, and means including a separate element for locking the latter in open position operative on removal of said connector plug.

55. In an electric circuit controlling mechanism, a switch arranged in a circuit and comprising a movable switch element, means for independently making and breaking one branch of the circuit, and means for locking the former element in open position respectively operative to effect locking and unlocking in different angular positions of the latter.

56. In an electric switch, a movable circuit closing element, a plurality of independently movable connector elements, and means holding the former in open position permitting movement thereof to closed position only when all of the independently movable connector elements are in operative position.

57. In combination in a controller, a controller handle and a plug in circuit with said controller, means for locking said plug rotatable on an axis parallel to but offset from the axis of rotation of said handle, and means for interconnecting said locking means and said handle whereby said handle, though inoperative to move said first mentioned means, may govern its movement.

58. The combination with a controller having a controller handle and a plug in circuit with said controller, of means for

effecting locking of said plug rotatable on an axis parallel to but offset from the axis of rotation of said handle, and means for interconnecting said rotatable means and said handle whereby the position of said handle controls the position of said rotatable means and vice versa though neither can move the other.

59. In combination, a pivotally movable switch element, a circuit controlling con-

necter movable at an angle to the plane of pivotal movement of the switch element, means for locking said connector against removal, and means cooperating therewith and operative to lock the switch against movement occupying its locking position when the connector is free to be withdrawn and while still in its operative position.

10 In testimony whereof I affix my signature.
MORRIS P. HOLMES.
